W. E. WILLIAMS.
CAST RIM DISK WHEEL.
APPLICATION FILED DEC. 8 1919.

Patented May 17, 1921.

UNITED STATES PATENT OFFICE.

WILLIAM ERASTUS WILLIAMS, OF CHICAGO, ILLINOIS.

CAST-RIM DISK WHEEL.

1,378,302.

Specification of Letters Patent. Patented May 17, 1921.

Application filed December 8, 1919. Serial No. 343,353.

To all whom it may concern:

Be it known that I, WILLIAM ERASTUS WILLIAMS, a citizen of the United States, a resident of Chicago, in the county of Cook 5 and State of Illinois, have invented a new and useful Improvement in Cast-Rim Disk Wheels, of which the following is a specification.

My invention relates to wheels wherein a 10 rolled plate disk forms the web of the wheel and is secured to the rim and to the hub, or either one of them, by what is known as "casting on" parts of the wheel. The point being that certain parts of the wheel are 15 formed from rolled material, which is placed in the molds and other parts are cast on, or poured on, in molten stage and allowed to cool in position on the parts.

The object of my invention is to produce 20 a very strong and a cheap wheel, and one possessing the merits hereinafter set forth.

Reference will be had to the accompanying drawing, in which Figure 1 is a front elevation of the wheel.

25 Fig. 2 is a section in the plane of the axes of the hub and a spoke through one-half of the wheel on a larger scale from that of Fig. 1.

In the drawing 1 indicates the ordinary 30 hub of an automobile truck wheel and 2, 3, 4 designate the front, rear and middle portions of the rim.

5 indicates a pressed steel disk, which forms the front face of the wheel and 6 indicates a pressed steel disk which forms the 35 rear face of the wheel.

7 indicates diagonal braces connecting 40 across the parts between the front and rear regions of the disk.

The rear edge 3 of the rim is supported 45 by a cast annular disk portion 8, which extends down and terminates at 9 where it is joined by the outside periphery of the inside pressed steel disk 6.

45 The middle section of the rim 4 is bridged across between the sections 2 and 3 by a series of flat tie sections 10 and these are stiffened by a series of cross internally extending flanges 11. Some of these flanges 50 extend down as indicated by the portion 12 and connect across to the cast disk portion 8, but not all of them do this.

The outer periphery 13 of the disk 5 and the periphery 14 of the disk 6, as well as 55 the edges around the circular hub hole, indicated by 15 for the disk 5 and 16 for the

disk 6, are punched out at intervals in the form of notches as shown in dotted lines in Fig. 1 and indicated by 17.

The bracing bars 7 and their ends likewise are prepared by punched holes, and the purpose of these holes or notches in the margins of the plates 5 and 6 and in the ends of the bars 7 is to permit the cast metal to flow into the notches or holes forming rivet-like connections of "cast on" metal. Further, the sharp corners or edges of the holes permit the fusing of the two metals together, the heat for this purpose coming from the molten metal of the casting. Further, with a plate having notched edges, there is a sort of an elastic effect produced in the extreme margin of the edge that aids in preventing shrinkage of the parts in cooling.

75 These cross rivets or notches also form detents that cause the cast on metal to shrink more or less uniformly, each section by itself, so that the shrinkage is taken up uniformly where it occurs, more or less regardless of what part cools or solidifies first after the metal is poured, for it is a common occurrence in making castings, to find that the shrinkage of a wide area has drawn the metal along with it and produced cracks in the weakest portions, or where the metal was slowest in cooling, the shrinkage being cumulative. By dividing the circumference into distinct shrinkage sections, the shrinkage is not cumulative and there is nowhere 80 enough to produce any crack, and thus the notches have a valuable secondary function.

85 The drawings show a wheel provided with screw seats 18, which are provided for the purpose of fastening thereto the brake band drum, which is normally secured through 90 the holes 19 by bolts or screws.

95 Bolt holes 21, are provided for the purpose of attaching anti-skid chains.

A complete wheel with rolled steel insert 100 webs can be made for less than a wheel entirely of cast metal, and besides, defective wheels are more rare, and the loss on a defective wheel is less. In other words this way of making a wheel is economical and 105 the wheels are far less likely to be under serious shrinkage strains. Still further, a double web wheel is not readily cast, partly because molten steel will not flow well in a narrow space and hence the web must be 110 made unduly thick; or a wheel with insert webs is lighter if of equal strength.

These wheels are used with solid rubber tires of the "pressed on" type and therefore the cavities 22, indicated in dotted lines in Fig. 1, are not seriously objectionable, because the base plates of those tires are made of metal and cover up such holes as 22 in the rim of the wheel.

In making a similar wheel as a casting, it has been found difficult to support the necessary central cores accurately in place between the spaces to be occupied by the two plates, or in other words it is difficult to have the plates of proper thickness at all points. By using pressed plate inserts, it is possible to have sand or cores supported by the inserts themselves, thus saving materially in the cost.

The dished or concave outward shape of my pressed disks or plates permits the same to come and go with a slight degree of resilience, both in the matter of accommodating the disk to shrinkage of the cast parts of the wheel, and also affords having a slight resilience for the wheel in service.

25 What I claim is:—

1. In a disk wheel, two outwardly divergent rolled metal wheel disks centrally connected by a cast-on hub holding the central margins widely separated and having 30 their outer and more widely separated margins held in the marginal portions, respectively, of a broad-tread cast-on rim.

2. A wheel having a central hub and a broad tread rim both of cast metal, said rim 35 having near one margin an integral, dished disk extending across a material portion of

the space between the rim and hub, an annular pressed plate disk extending inward from said cast disk to the hub, and a larger disk of like metal extending from the opposite marginal portion of the rim to the hub, both the pressed metal disks being held at their inner and outer margins by cast-on connection.

3. A wheel having a cast hub and a broad 45 tread cast rim provided with stiffening plates extending inwardly in radial planes, having one margin connected to the hub by a cast-in rolled metal disk and having the opposite margin connected to a part of the 50 hub distant from the disk first mentioned by integral annular cast portions connected by a smaller cast-in disk of rolled metal.

4. In a wheel of the class described, a double disk wheel having rolled pressed steel 55 disks forming the webs and the said disk connected to the hub and to the rim by means of "cast on" methods, together with diagonal bracing between the plates composed of a series of bars extending diagonally across 60 from the fastening of one plate at the hub over to the fastening of the other plate at the rim and the said braces secured in the assembly by having cast on their ends the metal of the rim and the hub.

Signed at Chicago, in the county of Cook and State of Illinois, this 1st day of December, 1919.

WILLIAM ERASTUS WILLIAMS.
